BROADCAST RECEIVER APPARATUS FOR
AUTOMATIC PRESS BUTTON TUNINGEugen Steffens, Berlin-Siemensstadt, Germany;
vested in the Alien Property CustodianApplication February 15, 1941, Serial No. 379,065
In Germany September 30, 1939

7 Claims. (Cl. 74—10)

Broadcast receiver sets with push-button or press-button (automatic) tuning are often furnished with a distinct release button or an equivalent device by the agency of which on changing from press-button tuning to normal tuning by means of a continuously revoluble knob control, the keyboard or the bank of press or push buttons is rendered inoperative. In the conventional type of keyboard, as will be remembered, the press-button stays immobile or locked and is allowed to return to its inoperative position only when another press button is actuated. Thus, if a change is to be made from press-button tuning to the continuous tuning by knob, it is either necessary to operate a distinct release button which causes the depressed button to return to its inactive position or else the keyboard for automatic tuning must be rendered inoperative by some other ways and means. However, such additional accessory device as well as the provision of a release key involves the drawback that the operation of broadcast receivers with press-button tuning control mechanism is made more complicated, not to mention the fact that such devices involve additional cost. Now, these drawbacks are obviated by the invention. In broadcast receivers as here disclosed the press button or key last set and operated is released from its locked and depressed position in a simple way by turning the rotary knob connected with the tuning means and serving for continuous tuning. When setting the rotary condenser by the aid of the tuning knob the arresting or locking of the press button bank is automatically and positively released or tripped. To this end, for arresting the press buttons, a slide-like arrester device may be provided which is so designed that when setting the tuning means by the continuously operating adjusting device the press buttons are unlocked.

An exemplified embodiment of the invention is shown by way of example in the appended drawing. Only one of the push buttons of the whole bank normally provided is here shown in its entirety, an additional push-button being shown partially. The press rod 1 which is connected with the button or key is fitted with a striker piece or actuator indicated at 2. When the press or push rod 1 is depressed, the said striker piece 2 comes to bear against the rods 3 and 4 of the rocker 5. Through the intermediary of the said rocker 5 and of the tooth-wheels 6 and 7 the rotary condenser shaft 8 or other shaft serving to move the tuning means is set. After the rocker 5 has been thus operated the push

rod occupies its innermost position. In this position the push rod 1 is arrested and locked by the aid of an arrester device consisting of a slide or latch bar 10. By means of a spring 9 the latch bar 10 is pressed firmly against the push rod 1. For arresting or preventing the release of the push rod it is fitted with a catch 11. For releasing the push rod 1, there is provided a spring 12 which is so proportioned that its retractile force just suffices to return the push rod 1 and when liberated by the slide 10. The pressure of the slide 10 against the push rod 1 due to spring traction by the spring 9 is so proportioned that by the pull of the spring 12 the slide 10 can not be moved by the catch 11. If, then, by actuation of the rotary knob 13 or some other rotary knob connected with the tuning means by way of a transmission gear, cable or the like drive the rotary condenser shaft 8 is moved, then, through the intermediary of the tooth-wheels 7 and 6 also the rocker 5 and therewith the rods 3 and 4 are turned. By these rods 3 and 4 pressure is brought to act upon the striker 2 which will be exerted according to the direction of rotation upon the lower or the upper part of the striker. The pressure which is exerted upon the striker piece 2 becomes added to the traction power of the spring 12. This pull will suffice to depress the slide 10 by the catch 11, with the result that the push rod 1 is able to fly back into its starting position.

What I claim is:

1. In tunable radio signalling apparatus adapted to be tuned by adjustment of a continuously variable tuning means, a manually controlled device capable of only rotary motion for operating said tuning means, a push button tuning instrumentality of the type wherein the depression of a push button mechanically adjusts the tuning means to a predetermined position, means for holding an operated push button in a depressed position until released by the subsequent operation of another push button, and means coupled with said manually controlled device and acting only upon rotation thereof in either direction for effecting the release of any depressed push button of said push button tuning instrumentality.
2. In a tunable radio receiver including a continuously variable tuning means, a manually operable device capable of only rotary motion for operating said tuning means, a push button tuning instrumentality for operating said tuning means, means including a locking bar and a cooperating catch for holding an operated

push button in a depressed position and for releasing the push button upon the subsequent operation of another push button, and means coupled with said manually operable device and acting only upon rotation thereof in either direction for forcing the catch of any depressed push button out of engagement with said locking bar to thereby effect the release of such a push button.

3. In tunable radio signalling apparatus provided with a continuously variable tuning means, a manually operated tuning knob capable of only rotary motion coupled to said tuning means for positioning said variable tuning means, a push button tuning instrumentality operatively connected to said variable tuning means, said tuning instrumentality including a plurality of operable push button devices each thereof acting upon operation to effect the adjustment of said tuning means to a predetermined position, resilient means for biasing each of said push buttons toward their respective released positions, a locking bar, a catch on each of said push button devices cooperating with said locking bar for holding an operated push button device in a depressed position against the action of said resilient means until the subsequent operation of another one of said push buttons, and means acting only upon the rotation of said tuning knob in either direction for forcing the catch of any depressed push button device over the locking bar to thereby release the depressed push button whereby its associated resilient means returns the same to its released position.

4. In tunable radio receiver provided with a continuously variable tuning means, a manually operated tuning knob capable of only rotary motion coupled to said tuning means for positioning said variable tuning means, a push button tuning instrumentality operatively connected to said variable tuning means, said tuning instrumentality including a plurality of operable push button devices each acting upon operation to adjust said variable tuning means to a predetermined position, means for returning a depressed push button to its released position, a pivoted bail, means on each of said push buttons cooperating with said bail for latching an operated push button in a depressed position against the action of said returning means and in the process of the depression of its push button to act upon said bail to cause the same to release any previously operated push button, and means acting only upon operation of said tuning knob in either direction for unlatching said latching means of any depressed push button to thereby release the depressed push button.

5. In tunable radio signalling apparatus provided with a continuously variable tuning means, a manually operated tuning knob capable of only rotary motion coupled to said tuning means for positioning said variable tuning means, a push button tuning instrumentality operatively connected to said variable tuning means, said tuning instrumentality including a plurality of operable push button devices each acting upon operation to adjust said variable tuning means to a predetermined position, means

for applying a returning force to a depressed push button, a movable locking bar having a locking position and a releasing position, resilient means for biasing said bar toward its locking position, means including a catch on each of said push buttons cooperating with said locking bar when the locking bar is in its locking position, for holding an operated push button in a depressed position against the action of its returning means and while the push button is being depressed, to move said bar temporarily to its releasing position to thereby effect the release of any previously operated push button device, and means acting only upon operation of said tuning knob in either direction for causing the catch means of a depressed push button to force said locking bar to its releasing position to thereby release the depressed push button.

6. In a radio receiver provided with a variable tuning reactor, a pivoted rocker bar, coupling means interposed between the rocker bar and the tuning reactor, push-button tuning mechanism including a plurality of reciprocable push-button devices each thereof acting upon operation to effect a predetermined adjustment of the rocker bar and coincidentally the tuning reactor, a spring for biasing each push-button device to its inoperative position, a spring-pressed locking bar, a catch on each of said push-button devices cooperating with said locking bar for holding an operated push-button device in a depressed position against the action of its spring until the subsequent operation of another one of said push-buttons, and a manual control member associated with the tuning reactor acting upon rotation thereof in either direction from the position of adjustment determined by a previously operated push-button for applying to the rocker bar through said coupling means sufficient force which is additive to that of the biasing spring associated with the push-button device to overcome the force of the spring-pressed locking bar whereby the depressed push-button is released for return to its inoperative position.

7. In a radio receiver provided with a variable tuning reactor, a first means for adjustably setting said reactor comprising a pivoted rocker bar mechanically coupled to the tuning reactor, a plurality of reciprocable push-button devices each thereof acting upon operation to effect a predetermined adjustment of the rocker bar and coincidentally the tuning reactor, a locking bar, a catch on each of said push-button devices cooperating with said locking bar for holding an operated push-button device in a depressed position until the subsequent operation of another one of said push-buttons, and a second means associated with the tuning reactor for adjusting said reactor independently of the first means, said second adjusting means acting upon rotation thereof in either direction for effecting release of a previously operated push-button by the locking bar through the intermediary of the pivoted rocker bar whereby the depressed push-button is released to enable it to return to its inoperative position.
